DRY KILN AND THE ART OF KILN DRYING

James Forrest Cobb, Portland, Oreg., assignor to
Moore Dry Kiln Company of Oregon, a corpora-
tion

Application April 26, 1932, Serial No. 607,651

6 Claims. (Cl. 34—46)

My invention relates to improvements in dry kilns and in the art of kiln drying.

An object of my invention is to more effectively and efficiently control the drying process.

5 Another object of my invention is the improvement in the art of drying which consists of employing a greater rate or volume of kiln atmospheric circulation across the surfaces of the stock being dried at an initial stage of the drying process and employing lesser rate of circulation at a later stage of the drying process.

10 Another object of my invention is to accomplish better kiln drying of lumber products and other colloidal substances by the reduction of the circulation rate across the stock to be dried after the fibre saturation point of the stock has been reached.

15 Another object of my invention is to increase the efficiency of drying by employing a faster circulation rate of kiln atmosphere across the stock while the drying capacity of the circulating atmosphere is less, and employing a lesser rate of circulation across the stock at a later stage of the drying process when the drying capacity of the circulating atmosphere is greater.

20 Another object of my invention is to employ novel means for effecting a greater rate of circulation at an earlier stage of the drying process, and a lesser rate of circulation at a later stage of the drying process.

25 Another object of my invention is to effect a correlative control of temperature, humidity and circulation of the atmosphere within the kiln at the initial and at the final stages of the drying process.

30 Another object of my invention is to provide a novel variable speed drive means for a rotative shaft.

35 Another object of my invention is to provide a novel means of changing the rate of rotation of a driven member.

Another object of my invention is to provide a novel air circulating system for a dry kiln.

40 Another object of my invention is to provide a novel heating system and method of its control for a dry kiln.

45 Another object of my invention is to effect zone control of heat, humidity and circulation within a kiln.

50 Another object of my invention is to effect novel zone control or two-stage drying in a progressive dry kiln.

55 Another object of my invention is to control the differential of temperature and humidity between a control point or points at one end of the

kiln and the temperature and humidity remote from the control point or points at the other end of the kiln.

Another object of my invention is to control the rate of circulation within the kiln according 5 to the deviation of the relative humidity or the wet bulb temperature within the kiln from the set point of the controller.

When lumber dries it shrinks, and if the outside shell of the stock dries too fast it shrinks 10 over a comparatively wet interior that has not shrunk. As a result, the outside surface of the stock develops enough crack or check to make up the difference in shrinkage, thus damaging the lumber. This is particularly evident at the ends 15 of the stock, which naturally dry faster than the other parts.

Also, the moisture in lumber is classified into two kinds known as "free moisture" and "hygroscopic moisture", the first being contained in the 20 cell cavities like honey in a comb, and the second being absorbed by the cell walls. The free moisture transfuses freely and may be removed rapidly, and until it is removed from the surface of the stock substantially no shrinkage takes place. 25 The removal of the hygroscopic moisture, however, is a slower process and depends upon the diffusion rate of moisture from the inside of the stock through the fibrous structure to the surface, where it may be wiped off or absorbed by 30 the surrounding or circulating atmosphere. This diffusion rate is less than one half as great as the transfusion rate of the free moisture from the stock.

If the drying rates are made to conform sub- 35 stantially to the transfusion and the diffusion rates of the stock respectively, at the earlier and later stages, then the drying progresses evenly, both over and through the pieces of lumber and no casehardening and checking occurs. 40

The drying rate of a kiln atmosphere is a function of its humidity, temperature and circulation. Heretofore, the proper regulative adjustments of humidity and temperature only have been given consideration, and kiln operators have in the past endeavored to solve the drying problem involved with one of the factors missing,—namely, a properly controlled circulation. 45

What I have done is to make use of not only 50 temperature and humidity in the equation, but also of the factor of circulation, rate or volume of air per minute, which gives a useful result that is entirely new.

I have discovered that it is impossible to con- 55

trol the drying rate of stock below the fiber saturation point adequately and economically by varying either the relative humidity or temperature, or both, of the drying atmosphere. Best results can be obtained by a proper control of relative humidity and temperatures and, in addition, a proper control of the rate or volume of circulation. When a proper reduced rate or volume of circulation is used during the latter stage of the drying process, the removal of moisture from the surface of the stock is made to substantially conform to the diffusion rate, and a material improvement in the quality of drying results therefrom. Relative humidities of the circulating atmosphere, lower than in the old practice, may be used during this stage because of the controlled circulation. In other words, when drying out, specifically, the hygroscopic moisture, best results are obtained by maintaining a practicable degree of relativity between the temperature necessary to effect diffusion, and the humidity of the drying atmosphere, and also a reduced rate of circulation across the stock. Different woods will require variations of all three factors, and hence it is not possible to give even a general table or rule relating thereto. However, a skilled dry kiln operator, being supplied with the underlying idea, will be able to apply the proper variation in any given case.

30 What constitutes my invention will be herein-after specified in detail and succinctly defined in the appended claims.

In the accompanying drawings wherein my invention is illustrated, I present in preferred form 35 of embodiment.

Figure I is a partial horizontal cross section, of one of my kilns taken in a plane above the floor, with piping connections omitted.

Figure II is a partial longitudinal vertical section partially diagrammatic, taken along the lines 40 II-II of Figure I.

Figure III is a transverse section taken along the lines III-III of Figures I, II, VIII and IX, illustrating stock loads within the kiln.

45 Figure IV is a transverse vertical section taken along the lines IV-IV of Figures I and II.

Figure V is a plan view of a motor and drive mechanism which may be used for one of my kilns.

50 Figure VI is a front elevation of Figure V.

Figure VII is a side elevation of Figure VI.

Figure VIII is a partial horizontal section of an alternate design of kiln to that shown in Figure I illustrating features of my invention, with piping 55 connections omitted.

Figure IX is a partial longitudinal vertical section partially diagrammatic, taken along the lines IX-IX of Figure VIII.

Figure X is a side elevation of an alternate design of heating system for progressive kilns to that illustrated in Figures I and II.

Figure XI is a side elevation of another alternate design of heating system.

Figure XII is a cross sectional detail of a diaphragm valve employed in Figure IX.

Figure XIII is a cross sectional detail of a motor lever employed in Figures VIII and IX.

Figure XIV is a partial detail cross section of the jack screw.

70 Figure XV is a detail of motor switch for changing the fan R. P. M. of the kiln.

Referring to the numerals on the drawings, I illustrates the floor of the kiln, 2 and 3 the side walls, 4 the roof and 5 the partition floor. The 75 functions of the partition floor may be accom-

plished by the bottom or top layer of the stock loads 6 and 7, for example, which may be within the kiln. The kiln is preferably equipped with a door 8, or doors 9 and 10, at one or both ends of the kiln.

Stock loads 6 and 7 are preferably supported by bunks 12 which may be carried on trucks 13 mounted to roll on track rails 14 extending through the kiln. The tracks are carried on suitable supports such as beams 15, which are 10 preferably supported by the walls 2 and 3, and which may support the partition floor 5.

The stock loads 6 and 7 are preferably stacked in layers having stickers 16 between layers 17 of stock, providing interstices 18 open for air circulation within the kiln. The stock is preferably stacked edge to edge between stickers on the stock loads, when cross circulation is used, but it is to be understood that the stacking may be of any preferred form and this invention is not limited 20 to any particular kind of stacking, or to any particular direction of air circulation within the kiln.

The difference between so-called charge and progressive dry kilns is in the manner of their 25 operation. I preferably provide a kiln which may be operated progressively—that is, a kiln in which green stock is put into the green end at periodic intervals and dry stock is removed from the dry end at periodic intervals. In progressive kilns the 30 circulation rate and the schedule of dry conditions is varied within the kiln from one end to the other. This principle may also be applied to charge kiln operation in which each kiln is filled with lumber or other material to be dried, and the 35 drying conditions are varied from the beginning to the end, during the drying process. My invention relates to the method of drying stock in both progressive and charge type kilns.

I have illustrated in Figures III and IV single 40 track kilns; however, it is understood that multiple track kilns may be employed. It is also understood that the fans located below the tracks within the kiln, may be a preferred form of embodiment.

In progressive kilns I preferably provide zone 45 control of temperature, humidity and circulation, considering, for example, that there may be preferably two zones in the kiln—preferably one at each of its ends. In some cases more than 50 two zones may be employed.

In progressive kilns I preferably provide a greater rate and volume of circulation across the stock at the green or entering end of the kiln to evaporate the free water which transfuses 55 freely to the surface. At this end I also preferably provide a relatively low temperature and a relatively high humidity. In the green end zone when a lower temperature and a higher humidity are employed, the drying capacity of this atmosphere is lower and a relatively higher rate of circulation is essential. At the dry end of the kiln, which the stock reaches after it is dried to the fibre saturation point, and the stock contains only hygroscopic moisture, I preferably provide a lower rate and volume of atmospheric circulation, also a higher temperature and a lower relative humidity. The lower rate of circulation in the dry end zone is practicable because the drying capacity of the atmosphere is greater. The reduced rate of circulation at this latter stage also increases the quality of the drying by reducing the tendency to caseharden, reducing the loss of steam through use of steam humidifying 70 75 80 85 90 95 98

sprays, and reducing the power consumption for unnecessary circulation.

When charge kilns are used I preferably provide a faster rate of circulation at the initial stage 5 of the drying process, together with a higher humidity and lower temperature, for the same purpose as described for the green end of progressive kilns, and at a later stage, after the fibre saturation point of the stock has been reached, I 10 reduce the rate and volume of air circulation across the stock, increase the temperature and reduce the humidity for the same purpose as described for the dry end of progressive kilns.

When reference is made to the green end of a 15 progressive kiln or the earlier stage of the drying process in charge kilns I refer to the stage of drying in which the stock contains free water as well as hygroscopic moisture. When reference is made to the dry end of a progressive kiln, or to the 20 latter stage of the drying process in charge kilns, I refer to that stage of the drying process in which there remains only hygroscopic moisture within the stock.

I provide a plurality of heating systems 19—A, 25 19—B, 20—A, 20—B, 21—A, 21—B, 22—A and 22—B within the kiln supplied with steam through a supply pipe header 23 and having drain headers 24 with suitable connections and traps 30 not illustrated for trapping the condensation from the heating pipes.

The headers 23 of the heating systems 19—A, 19—B, 21—A and 21—B at the green end are fed through supply pipes 8—A and 8—B respectively from a source of steam supply not illustrated, and the headers 23 of the heating systems 20—A, 20—B, 22—A and 22—B at the dry end of the kiln are fed through the supply pipes 11—A and 11—B from a source of steam supply not illustrated. Each of the bottom headers 24 is drained and 40 trapped in any usual manner not illustrated.

The "A" and "B" units of each heating system are individual units. Either or both of them may be used to provide the amount of heat at each end of the kiln that may be required to maintain the 45 temperature schedule. The "A" and "B" units of each heating system are preferably individually and independently controlled, either by automatic control instruments or manually.

In progressive kilns I preferably employ greater 50 heating capacity at the dry end than at the green end of the kiln, as illustrated in Figures I and II. In Figure I the heating units 19—A, 19—B, 21—A and 21—B at the green end preferably have less heating capacity than the heating units 20—A, 20—B, 22—A and 22—B at the dry end of the kiln.

In some cases I employ graduated heating systems extending the full length of the kiln with greater heating capacity at the dry end than at the green end, and auxiliary heating units at the green end, at the dry end, or at both ends for individual control of temperature at the two ends of the kiln. Examples of such heating systems are illustrated in Figures X and XI.

The heating system illustrated in Figures X and XI may be used in progressive kilns when a temperature difference at the two ends of the kiln is desired. The top line of the heating system 55 extends preferably the full length of the kiln, and the second, or the second and third lines of the heating system 25 are located at the dry end of the kiln only. Experience has shown that in drying some classes of stock the relationship of not less than twice the heating capacity at the 70 dry end, than at the green end, gives best re-

sults in progressive kilns. I preferably provide auxiliary heating units 26 at the green end, as illustrated in Figures X and XI, also auxiliary heating units 27 at the dry end of the kiln. The auxiliary units 26 and 27 are preferably separately controlled and may be used to raise the temperature at the green and dry ends respectively of the kiln, or if the heating units are in use, they may be cut off at either end to reduce the temperature. 5

When only separately controlled heating units 10 of substantially the same capacity are employed at the green and dry ends of the kiln, as illustrated in Figures VIII and IX, I may maintain such temperature difference between the two ends as desired by varying the amount of heating 15 surface in use at the two ends of the kiln, and by utilizing the heating units at the dry end during longer periods of time than at the green end.

When charge kilns are used I preferably employ a uniform temperature the full length of the kiln 20 to give uniform drying. This may be accomplished by employing separately controlled heating systems at each of the two ends of the kiln or by employing a single heating system extending the full length of the kiln on one side and two 25 individual heating systems, each extending half the length of the kiln, on the other side. By employing separate temperature and humidity controllers 30 and 31 at the front and back ends respectively of the kiln, I may automatically maintain 30 a uniform temperature throughout the kiln. These same controllers 30 and 31 may also be employed to automatically maintain uniform humidity at the front and back ends respectively of the kiln, by controlling independent humidifying 35 spray pipes, independent fresh air conduits and independent ventilators at the two ends respectively of the kiln. The controllers may be set to provide the same drying conditions at each end, or they may be set to maintain slightly different drying conditions if desired to provide a faster drying rate of wetter stock, for example, that may be located at one end of the kiln, or one of them may be set to maintain a slow drying rate for drier stock which may be at one end of a 40 45 kiln charge.

In kilns in which I employ separate air circulating systems and having two-speed control of the rate of rotation of the fans and having the same size of fans at each end of the kiln, and individual heating systems, ventilating systems, fresh air systems and humidifying systems at each of the two ends respectively of the kiln, I may use the kiln for charge operation or for progressive operation, in either method of operation of which, 50 a faster rate of circulation, a lower temperature, and a higher humidity, for example, may be maintained at first stage of the drying process, and a lesser rate of circulation, a lower humidity, and a higher temperature, for example, may be 55 maintained at a later stage of the drying process by separately controlling the systems at the two stages.

By having the facilities above described I am 60 able to maintain the desired conditions for flexible control of temperature, humidity and circulation to give two stage drying for either charge type or progressive kilns.

In a charge kiln I preferably employ separate controls for the heating, humidifying and air 70 circulating systems at each end of the kiln. For example, a separate temperature and humidity recorder controller is preferably used having thermostatic bulbs at each end of the kiln and a controller for effecting different rates of rotation 75

of the fans is preferably employed at each end of the kiln. These controls are preferably set to maintain the same conditions of temperature, humidity and circulation at each end of the kiln.

5 If the temperature or humidity of the atmosphere of the kiln at the bulbs varies at one end in relation to that at the other end or from a pre-determined set point of dry or wet bulb temperature of the controller at that end, caused, for example, by difference in the drying rate of the stock at that end of the kiln in relation to the drying rate at the other end, the controller at that end will automatically actuate the heating and/or humidifying, and/or air circulation systems at that end. For example, if the dry bulb temperature of the atmosphere is low at one end, caused by faster drying rate of the stock at that end, the controller will open the diaphragm valves 34, for example, to supply steam to the pipes 21 until the temperature is raised to the set point. If, for example, the wet bulb temperature of the atmosphere is low at one end of the kiln in relation to that at the other end, the wet bulb controller will actuate the fan speed control to cause the rate of rotation of the fans to be reduced at that end and/or the humidifying sprays to be turned on and/or the ventilators to be closed. When the wet bulb temperature of the circulating atmosphere is raised to the set point, the rate of rotation of the fans will automatically be increased to high speed, and/or humidifying sprays turned off and/or the ventilators opened. If the moisture content of the stock is greater at one end of the kiln than at the other end, under equal conditions of heat, humidity and circulation, the end having the greater moisture content will require more heat and a greater rate of circulation because there will be a tendency towards a lower temperature and a high humidity at that end. The end having the lower moisture content stock will tend to have a higher temperature and a lower humidity, which would require less heat and a less rate of circulation if the wet bulb temperature drops below the set point of the controller at that end.

45 The automatic controllers 30 and 31 are preferably of any well-known type, each controller having thermostatic dry and wet bulbs within the kiln. For example, the controller 30 has a dry bulb 32 and wet bulb 36, while the controller 31 has a dry bulb 33 and a wet bulb 37. The dry bulbs 32 and 33 control the dry bulb temperature at the two ends of the kiln by actuating the controllers 30 and 31 respectively to open diaphragm valves 34 and 35 respectively, by air pressure to the controllers through the pipe 195 from an auxiliary air supply not illustrated, through the air pipes 100 when the dry bulb temperature within the kiln at the two ends drops below the set points. Similarly the wet bulbs 36 and 37 control the wet bulb temperature within the kiln at the two ends by actuating the controllers 30 and 31 respectively, to open the diaphragm valves 67 and 68 by air pressure from an auxiliary air supply not illustrated through the air pipes 101, when the wet bulb temperature within the kiln at the two ends respectively, drops below the set points. The wet bulbs 36 and 37 are preferably kept wet by wicks 41 in water boxes 40 by a supply of water from the pipes 42 from a source not illustrated.

The circulating system preferably comprises rotary driven fans, for example, 45 and 46, operatively mounted on one or more shafts 47, or 47 and 48, carried on suitable bearings 49, which are

supported by bearing stands 50. The bearings 49 and thrust bearing 60, are provided with lubrication preferably through oil cups 51, which may be located within or outside of the kiln. The fans 45 and 46 may be either right hand or left hand, but they are illustrated as left hand fans 45 and right hand fans 46. The fans 45 are illustrated of larger diameter and having larger circulating capacity than the fans 46. Fans 45 are located at the green end of a progressive kiln and the fans 46 are located at the dry end of a progressive kiln (see Figures I and II for example). If charge operation is employed, it is understood that the fans may be of substantially the same circulating capacity, for example, and are designated 45 and 52 in Figures VIII and IX, but will be rotated at different rates of speed at different ends of a progressive kiln, or rotated at the same R. P. M. at high speed at the beginning of the drying process in charge kilns, and at the same R. P. M. at low speed at a later stage of the drying process in charge kilns, to accomplish different rates of circulation across the stock at different stages of the drying process in both progressive and charge type kilns.

The air circulating system shown in Figures I and II is that described in Patent #1,680,013, issued August 7, 1928. However, it is understood that the principles and features of my present invention may be adapted to kilns having any design of air circulating system to which they may be applied. In Figures I and VIII I illustrate a substantially vertical wall 28, which is a partition extending substantially the full length of the kiln in a zigzag direction, having fans 45 and 46 mounted at intervals in openings in said wall provided for them, on one or more shafts 47, or 47 and 48. The fans may also be mounted in any other manner so long as they effect a circulation across stock which may be stacked in any preferable manner within the kiln.

A fan shaft 47, in Figures I and II, is rotated by suitable driving means located preferably outside the kiln, such as, for instance, an electric motor 54 and a belt 55. Means are provided for reversing the circulation at will, such as by any well-known type of reversing switch not illustrated.

I preferably maintain independent drying conditions at the green end and dry end zones of a progressive kiln. This is accomplished by employing independent heating, humidifying, circulating and ventilating means at the green and dry end zones of the kiln which may be independently and individually controlled.

In charge type kilns I preferably provide a variable speed driving means for kilns, which may be an individual variable speed motor rotating the fans at each of the two ends of the kiln, or constant speed motors 58, or 58 and 59, together with other means comprising stepped pulleys. The stepped pulley on the motor 58 has two driving faces, one 61 of larger diameter, and the other 62 of smaller diameter. The driven pulley comprises a face 64, which is of smaller diameter and is aligned to be driven by the driving pulley 61. The other face 65 of the driven pulley is aligned to be driven by the smaller driving face 62 of the driver pulley.

I preferably provide stepped pulleys which will give, for example, a reduced fan shaft R. P. M. at the later stage of the drying process, requiring about half as much motor horsepower as the greater R. P. M. of the fan shaft at the initial stage.

A motor 59 and its variable speed mechanism, similar to and having the same characteristics as the motor 58 and its variable speed mechanism, is preferably provided at the opposite end of the kiln.

The motors 58 and 59 are mounted on suitable bases which are pivoted on one edge adjacent to the driven shaft in such manner that the weight of the motor will be exerted to maintain tension on the drive belt 66. The base comprises two main parts—the rigid base 72, and the pivoted plate 73, which is hinged on one of its edges to the rigid base 72 by the hinge pin 74. The rigid base 72 is preferably bolted or otherwise rigidly fixed to a suitable support 71 by anchor bolts or any suitable means. The motor is mounted directly on the pivoted plate 73 by bolts. Provision is made for the motor to slide on the pivoted plate toward or away from the hinge pin 74. For example, it may be moved toward the hinge pin by loosening the bolts 76, and by loosening the screws 77, and by tightening the screws 78 against the opposite side of the motor.

In addition to the weight of the motor, I preferably provide means such as springs for maintaining belt tension. For this purpose I provide a threaded rod 70, or other means, which is hinged or otherwise attached to a clevis 81 on the rigid base 72, or on its supports 71. Tension is transmitted to the belt through a bracket member 82, which is attached to the pivoted plate 73, to which the motor is fastened, by means of a thumb jack screw 83, having a shoulder 84, and a collar 85. A suitable opening 86 in the pivoted plate is provided to allow free turning of the jack screw 83 in the pivoted plate. The jack screw is threaded into the bracket 82.

The bracket 82 may be of any shape, but is illustrated in the form of a Z and has means for attachment to the pivot plate, such as an opening 86 at one end and means connecting with a spring at the other end, such as an opening 87. The opening 86 at one end is threaded for the jack screw 83, and the opening 87 at the other end is large enough to pass freely over the threaded rod 70.

The threaded rod 70 passes through the opening 87 in the bracket 82 and has two springs 79 and 80, one on each side of the bracket 82 being separated therefrom by washers 88. Washers 89 separate the springs 79 and 80 from the nuts 90 and 91 respectively, which are threaded on the rod 70. By adjustment of the nuts on the threaded rod 70, change in the tension of the springs 79 and 80 is effected. By adjusting the nuts 90 and 91 upwardly, the drive centers of the driver and driven pulleys are reduced. By adjusting the nuts 90 and 91 downwardly, the drive centers of the driver and driven pulleys are increased.

The ordinary type of pivoted motor base does not permit a ready reversal of the motor. It works well in one direction of rotation when the tight side of the belt is adjacent to the pivot point of the pivot plate, but does not work so well in the reverse direction of rotation when the tight side of the belt is on the side opposite to the pivot point. In other words, it does not maintain uniform belt tension for both directions of motor rotation.

When the tight side of belt 66 is at the top, the point of belt pull is elevated above the pivot point of motor base so that its level action is much greater, tending to raise the motor on the hinge

pin 74 as a pivot. The spring 80 is thus employed to augment the weight of the motor in this direction of rotation in order to maintain a tension on the belt equal to the tension produced by the weight of the motor when the bottom side of the belt is tight and the lever action tending to raise the motor is less.

The means of maintaining uniform belt tension for either direction of motor rotation overcomes the disadvantage of the ordinary type of pivoted motor base for reversal of rotation, and I am able to reverse the motors on my kilns without losing the proper belt tension.

The proper adjustment of the springs 79 and 80 accomplish this purpose. The spring 80 is of sufficient capacity to exert a force downward to maintain belt tension when the motor is rotating in a clockwise direction as shown in Figure VI equal to the tension on the belts when the motor is rotating in an anti-clockwise direction as shown in Figure VI. The springs 79 and 80 are preferably selected to provide sufficient strength for their purpose, there being but little compression on them when properly adjusted. The springs 79 and 80 also permit a relative movement of the belt pulleys which aids in maintaining uniform belt tension. The effective weight of the motor for increasing or reducing belt tension may be changed by adjustment of, for example, the nuts 90 and 91. In fact, this adjustment provides an additional means of regulating belt tension and of maintaining constant belt tension in either direction of rotation of the motor or driven pulley.

I also provide means for facilitating the change of speed of the driven shaft by shifting the belt 66 from the large drive pulley 61, and the small driven pulley 64 to the small drive pulley 62, and the large driven pulley 65, and vice versa. This means may be accomplished by the use, for example, of the thumb jack screw 83, one end of which is attached to the pivot plate 73, and the other end of which is threaded into one end of the bracket 82. The other end of the bracket 82 is provided with an opening 87, through which the threaded rod 70 passes. When it is desired to shift the belt, the jack screw 83 may be screwed out of or detached from the bracket 82, and the motor raised. After the shift of the belt is made, the motor can be lowered by screwing in the jack screw 83 to tighten up the belt, aided by the force of gravity depending on the weight of the motor and the strength of the spring 80. Some adjustment of belt tension may be obtained by the adjustment of the jack screw.

I preferably provide large and small driving and driven pulleys in such relationship that the position of the motor and the adjustment of the springs will be relatively the same with either fan speed for any given length of belt. In some cases, however, it may be necessary to use two belts, one for each driven pulley speed, to accomplish this result.

It is understood that the fans for effecting circulation within the kiln may be of any preferred type and that the design of the kiln may be of any preferred type. The principle involved in this invention will apply to any design or type of kiln, in which varying rates of circulation may be applied across the stock at different stages of the drying process. This invention is not limited to the design of kiln shown, but may be applied to external fan kilns or internal fan kilns of the designs well-known in the art.

In Figure I illustrating a progressive kiln, I have shown a cross circulation type kiln employing a

zigzag duct system; except that I have disclosed the use of larger fans, or fans having a greater circulating capacity at the green end of the kiln and smaller fans, or fans having a smaller circulating capacity at the dry end of the kiln. When in operation these fans exhaust the atmosphere from one side of the kiln and deliver it to the other side through the stock and thence in continuous operation. However, my invention is not limited to any one design of kiln.

In both charge and progressive kilns I preferably provide individual humidifying spray systems 122 and 123 at the two ends of the kiln respectively, subject to separate control, which permit separate control of the spray to control the relative humidity according to a predetermined amount at different stages of the drying process.

I also provide ventilators 120 and 121, which are separately controlled and mounted in series at the green and dry ends respectively of the kiln. A series of ventilators 120 and 121 may be subject to automatic control by the controllers 30 and 31 respectively, being actuated by the wet bulb temperature, for example, or they may be operated by hand to maintain a desired wet bulb temperature at the two ends of the kiln. The ventilators 120 also may be operated in conjunction with the separately controlled fresh air conduits 94 and 95, having fresh air doors 96 and 98, and the ventilators 121 may be operated in conjunction with the separately controlled fresh air conduits 92 and 93, having fresh air doors 97 and 99.

The ventilators may be of any well known or preferred type. For example, I illustrate dampers 148 in ventilating stacks 120 and 121 through the roof 4 of the kiln. The dampers are mounted on the rods 149 and 150 which may be rotated to adjust the ventilator openings at the green and dry ends of the kiln respectively. The ventilating stacks may be of any preferred number and may connect with any portion of the kiln.

Fresh air conduits 94 and 95, having fresh air doors 96 and 98 respectively, are on two sides of one end of the kiln and fresh air conduits 92 and 93, having fresh air doors 97 and 99 respectively, are on two sides of the other end of the kiln.

I provide suitable ports 145 in the fresh air conduits, preferably one in each conduit at each fan. These ports may be adjustable to distribute the fresh air intaken into the kiln to the several fans as desired. In cross circulation kilns the fresh air conduits on one side only may be used at both ends of the kiln.

I preferably provide ceiling baffles 146, also floor baffles 147, as may be required to direct the circulating atmosphere within the kiln, across the stock loads and prevent its passing around the stock loads.

An important feature of my invention is the method of drying, in which I preferably separately control the air circulating system, the heating system, the humidifying system, the ventilating system and the fresh air system within the kiln at different stages of the drying process. These systems may be controlled at the green end of a progressive kiln, or at the initial stage of the drying process to obtain a faster drying rate of the stock, at the initial stage of the drying process when the moisture content of the stock is high, and they may be separately controlled at the dry end section of a progressive kiln, or at the later stage of the drying process to maintain a different drying condition for the stock at a later stage in the drying process.

The controllers 30 and 31 may be of any well-

known type, preferably of the two pen type known as temperature and humidity recorder controllers, such as manufactured by well-known instrument manufacturers, controlling both dry and wet bulb temperatures. One is described in Bulletin #2907 issued by Moore Dry Kiln Company of Oregon in July 1929. The same results can be obtained by using two separate controllers, one for the dry bulb temperature and another for the wet bulb temperature. In this case both the dry bulb and wet bulb controllers are considered as the control instrument 30 or 31. An example of such single pen control instruments is described in the Patent #1,405,181 issued to E. H. Bristol, January 31, 1922, and another example is described in the Patent #1,582,868, issued to A. M. Dixon, April 27, 1926. These instruments preferably employ an auxiliary air supply to actuate diaphragm valves and motor levers to control the drying conditions within the kiln.

The diaphragm valves on both heating pipes and humidifying sprays may be of any well-known design, such for example, as illustrated in Figure XII, which may be opened with air pressure through the air pipes 100, to supply steam to the heating pipes within the kiln, or the air pipe 101, to supply steam to the humidifying sprays. Figure XII illustrates the design of diaphragm valves 34, 35, 67 and 68.

The diaphragm valve illustrated in Figure XII may be of any preferred design which opens with air pressure and closes with the release of air pressure in the diaphragm chamber 110. For example, the diaphragm valve consists of a valve body 151, a valve disc 152, a valve stem 153, and a diaphragm frame 166, through which the valve stem 153 passes. The valve frame 166 is attached to the valve body 151 by the nut 154. A diaphragm plate 155 is attached to a continuation of the valve stem 153, known as the valve rod 167, and rests against a rubber diaphragm 156, which separates the valve plate 155 from the diaphragm cover 164, providing an air tight chamber 110 between the cover 164 and the diaphragm 156, to which the air supply pipe 100 is connected. A spring 114 is placed between an adjustable nut 157 on the valve rod 167, and the valve spring support 168. The valve spring nut 157 is adjusted to provide the proper tension so that the valve will close automatically when air is released from the diaphragm chamber 110. The valve may be opened by pressure from an auxiliary air supply through the pipe 100 to the diaphragm chamber against the compression of the spring 114.

The motor levers actuating the fresh air conduit doors or the ventilators may be of any well-known type, for example, such as shown in Figure XIII. They are shown as closing the fresh air doors and ventilators by air pressure supplied through the pipes 102 and 103 respectively. Figure XIII illustrates the design of motor lever indicated as 106, 107, 108, 109, 116, 117, 125 and 126.

A motor lever, as illustrated in Figure XIII, actuates the fresh air doors, ventilators, and the speed changing mechanism for changing the speed of the fans. For example, a suitable motor lever comprises a main frame 107, a diaphragm cover 158, a diaphragm 159, with a diaphragm chamber 111 between the cover 158 and the plate 165. The diaphragm plate connects with a vertical lever 160, having holes in its upper end for adjustment, a weight lever 161 is fulcrumed on the diaphragm cover 158, one end of the weight lever is attached by a link 162 to the diaphragm lever 160, and the other end has pro-

vision for an adjustable weight 115 disposed on the opposite side of the diaphragm frame from the diaphragm plate so that the diaphragm weight 115 will remove the diaphragm lever 160 when air pressure from the diaphragm chamber 111 is released. When air pressure is admitted to the diaphragm chamber through the air pipe 103, the diaphragm lever 160 moves in the opposite direction. The diaphragm lever 160 is connected by a connecting rod 163 to a ventilator arm 194, of a ventilator damper 148 in a ventilator stack. When air pressure is admitted to the diaphragm chamber 111, the diaphragm weight lever 161 is lifted and the lever 163 moves to close the ventilators by means of movement of the diaphragm lever 160, the connecting rod 163, and the ventilator arm 194. When the air pressure is released from the diaphragm chamber, the ventilator is automatically opened by means of the pull of gravity on the weight 115 on the weight lever 161.

When the air supply is cut off to any of the diaphragm valves or motor levers described above, the air pressure in the air supply pipes, also in the diaphragm chambers 110 and 111 of the diaphragm valves or motor levers respectively is allowed to escape through an air leak in the instrument which is normally provided for this purpose, allowing the springs 114 or the counter-weights 115 on the diaphragm valves and motor levers respectively to close the diaphragm valves and open the fresh air doors and/or the ventilators of the kiln.

For example, when the temperature within the kiln at the position of the thermostatic bulb 32 drops below the set point on the control instrument, air from an auxiliary source is automatically supplied through the air pipe 100 to the diaphragm valve 34 to open the valve and supply steam, for example, to the heating pipes 19-A, 19-B, 21-A and 21-B, which heat the kiln at the green end, for example. As soon as the temperature within the kiln at the position of the control bulb 32 reaches the set point on the instrument, the auxiliary air supply is cut off from the air pipe 100 and the air pressure in the pipe 100 and in the diaphragm chamber 110 is allowed to leak out through an air leak in the controller 30 normally provided for this purpose.

When the wet bulb temperature within the kiln, for example, at the green end, drops below the set point of the thermostatic bulb 36, the control instrument automatically supplies air from an outside source through the pipe 101 to the humidifying spray diaphragm valve 61, to open it and supply steam, for example, to the humidifying sprays 122 at the green end of the kiln, through the pipe 102, to the motor levers 108 or 116 to close the fresh air doors at the green end of the kiln, and through the pipes 103 to the motor levers 106, to close the ventilators at the green end of the kiln.

As soon as the wet bulb temperature within the kiln at the position of the wet bulb 36 at the green end rises to the set point, the instrument automatically cuts off the supply of air in the pipe 101 and allows the air pressure in the pipe 101 and in the diaphragm chamber 110, also the air pressure in the pipe 102 and 103 and in the diaphragm chamber 111, to escape through an air leak in the controller 30 normally provided for this purpose. As a result the spring 114 closes the diaphragm spray valve 61, and the weights 115 on the motor levers respectively controlling the fresh air doors at the green end, open the

fresh air door 96 or 98, and the weights 115 also open the ventilators 120 respectively at the green end of the kiln.

The above description of the operation of diaphragm valves and motor levers at the green end of the kiln by the controller 30, applies also to the operation of the diaphragm valves 35 and 68 and the motor levers 107, 109 and 117 at the dry end of the kiln by means of the control instrument 31. It is understood that the drying conditions at the two ends of the kiln are controlled separately in progressive kilns to maintain a faster rate of circulation and preferably a lower temperature and a higher humidity at the green than at the dry end of the kiln. If an automatic temperature and humidity control instrument is not provided for this purpose, then the control may be accomplished manually.

It is understood that with either direction of air circulation within the kiln only one of the fresh air conduits and its corresponding fresh air door at either end of the kiln may be used in the cross circulation type of kiln, such as illustrated in Figures III, VIII and IX. The same applies to the operation of the ventilators. It is understood that the ventilators on one or both sides of the kiln at either end may be operated at any given time.

In drying refractory woods requiring a very particular drying schedule, I preferably control the rate of circulation within the kiln according to the deviation of the relative humidity, or the deviation of the wet bulb temperature from the set point of the controller. For example, when the relative humidity within the kiln is up to the set point of the controller 30 or 31, I preferably employ the high rate of circulation. When the relative humidity is lower than the set point there is danger of casehardening and damage to the material being dried. It is easier to maintain the wet bulb temperature setting and the humidity at the surface of the stock if the rate of circulation across the stock is reduced. I thus preferably reduce the rate of circulation when the wet bulb temperature within the kiln drops below the set point. This manner of operation also provides an additional safety factor in drying because in case the steam supply to the humidifying sprays is deficient, the fan speed will be automatically maintained at a reduced rate until the relative humidity is again raised to the set point. This manner of operation may be employed at the green or the dry ends of the kiln, or both ends, for example, in charge kiln operation, or I may employ this system of reducing the rate of circulation within the kiln at both ends, for example, in a progressive kiln when the relative humidity or wet bulb temperature at either end from any cause falls below the set point.

In order to accomplish this I preferably employ air motors 125 and 126 for actuating control means for varying the rate of circulation, according to the fluctuation of the wet bulb temperature from the set point of the controllers 30 or 31 respectively. When the wet bulb temperature within the kiln falls below the set point of controller 30, for example, air is supplied through the air pipe 130 to the air motor 125 to actuate the speed changing mechanism, reducing the motor R. P. M. of the motor 58 to low speed. Simultaneously with this operation, the humidifying sprays 122 are turned on and the fresh air doors 96 or 98, and the ventilators 120 are closed.

When the wet bulb temperature within the kiln

is raised to the set point, the air supply to the air motor 125 is cut off, allowing the air pressure in the air pipe 130 and in the diaphragm chamber 111 of the air motor to escape through an opening provided in the controller 30 for this purpose. The counterweight 115 on the air motor causes the operation of the speed changing mechanism to increase the R. P. M. of the motor to high speed. Simultaneously with this operation, the humidifying sprays 122 are turned off and the fresh air doors 96 or 98, and the ventilators 120 are opened in the same manner as described above.

The method of operation of the speed changing mechanism is described as follows:

Referring to the drawings Figure XV, 170 is a push button station for hand control for the variable speed motor 68 and may be of any suitable design. 171 is a drum switch for hand or automatic control. The air actuated motor lever 125 may be actuated by controller 30, to actuate a switch 128 to give automatic high or low speed control for the motor through use of a pole changing magnetic motor switch 176, having a contactor 172 for high speed of motor, and contactor 173 for low speed of motor.

Relays 174 and 175 normally closed are employed to insure proper operation of the pole changing magnetic switch 176, operating automatically through the electrical switch 128, operated by the air motor lever 125.

I preferably start the motor at full speed at the beginning of the operation by manual starting through the push button station 170, with the motor switch 171 set for hand control. The current starts at L-2 running through the high speed contactor holding-coil 177, through the push button station 170, through to L-3, thus completing the circuit. This closes the high speed contactor 172 and its auxiliary switches 181 and 182, which complete the circuit through the contactor holding-coils, preventing the high speed contactors from dropping out when the push button is released. The auxiliary switches 181 and 182 are mechanically interlocked with the high speed contactor 172, so that the auxiliary switches open when the contactor opens, and close when the contactor closes.

For connecting the motor for automatic operation from high to low speed, or from low to high speed, I throw the automatic control switch 171 to the automatic position.

When the wet bulb temperature within the kiln drops below the set point, on the controller 30, for example, the air operated switch 128 goes to the right, to the position for low speed, and it closes the circuit through the contacts of relay 175, allowing the current to flow through the contactor holding coil 180 for the low speed contact. This current also goes through the relay 174, which disconnects the high speed contactor just previous to the closing of the low speed contactor.

When the relative humidity or the wet bulb temperature within the kiln at either or both ends raises to or above the set point on the controller 30, for example, the motor speed is changed from low to high automatically as follows. The air operated pressure switch 128 is moved to the left to the position for high speed by means of the weight 115 after the air pressure from the pipe 130, and from the diaphragm chamber 111 is released through the opening provided in the controller 30. The circuit is closed through relay 174, allowing the current to flow through the contactor holding-coil 177 for the high speed con-

tact. This current, which comes from L-2, also goes through the relay 175, which opens the low speed contactor 173 just previous to the closing of the high speed contactor 172. The current goes through the holding coil 177 for the high speed contact, then back to L-3, which completes the circuit.

At any time, whether on hand or automatic starting, or whether the motor is running at low or high speed, the motor may be stopped by pushing the stop button of the push button station 170.

The air motor 125 may operate either slowly or quickly in closing switch contacts 128 as the current is carried by auxiliary switch contacts 183 or 181 immediately upon operation of either low speed or high speed contactor.

At the start of the kiln operation, I preferably start the motor manually by the push button station 170, and thereafter the air motor and the automatic circulation changing mechanism will automatically control the speed of the motor and of the fans within the kiln according to the fluctuation of the wet bulb temperature within the kiln from the set point of the controller 30 or 31. Provision is also made to disconnect the automatic operation of the air motor and the circulation changing mechanism so that the motor speed and the fan speed may be maintained at high speed at the beginning of the drying process if desired, and or, the speed of the motor and of the fans may be maintained at low speed at a later stage of the drying process. In other words, I preferably provide means for either automatic or manual variation in motor speed and fan speed within the kiln.

For example, in Figures VIII and IX, I illustrate a fan system, a heating system, a humidifying system, a ventilating system, and a motor speed controller for controlling the speed of the fan system, at each end of the kiln. As the wet bulb temperature in the kiln varies from the desired schedule at either or both ends of the kiln as set on the humidity recorder controller, of any well-known type, for example, the humidity recorder control instrument 30 automatically turns on the humidifying spray 122 by means of admitting air pressure to the diaphragm valve 67 and may reduce the fan speed to the low speed by actuating the switch 128 and, at the same time, close the fresh air doors 96 or 98 and ventilators 120 of the kiln by admitting air pressure to the motor levers 108, 116, and 106 controlling the fresh air doors and ventilators respectively. Similarly when the wet bulb temperature has reached or rises above the set point, the humidifying spray 122 is automatically cut off and the fresh air doors 96 or 98 and ventilators 120 may be opened, and the motor and fan speed increased to the original high speed by reverse action of the switch.

This method of operation reduces the hazard of damaging the stock in kiln drying, in that it more promptly and effectively brings the relative humidity to the desired point, because slowing up the rate of circulation across the stock causes an increase of humidity at the surface of the stock being dried by removing the moisture evaporated less rapidly thus increasing the differential between the temperature and the humidity at the position of the thermostatic control bulbs within the kiln, and the exit air from the stock load or the temperature and humidity at the surface of the stock remote from the control bulbs.

If desired, the steam spray may be dispensed

with entirely and the humidity controlled by reducing the circulation rate to slow speed, while the ventilators and fresh air doors are closed, and until the wet bulb temperature is raised to the set point on the controller, when high speed circulation is resumed.

At the beginning of the drying process when the stock contains free water, a considerably faster rate of circulation than it is economical 10 to continue through the drying period, is advantageous for conveying heat to and maintaining proper humidity at the surface of the stock. After the fibre saturation point is reached, a lower rate of circulation can be used, giving 15 maximum drying efficiency without penalizing the operation with an excessive power consumption.

The quality of drying is improved after the fibre saturation point of the stock is reached, by 20 reducing the rate of circulation to a minimum that will still give a uniform flow of air across all the stock. During the latter stage of the drying process, the transference rate is slow and less circulation is required to transmit heat to the 25 surface of the stock for purposes of evaporation. The reduced circulation rate thus prevents the formation of a steep moisture gradient within the stock, due to too fast surface drying during the latter stage of the drying process, which would 30 be accomplished by supplying too much heat to the surface of the stock, and also the necessity of furnishing more humidifying spray than would be required if the rate of circulation were not reduced.

35 In kilns there is a difference in the temperature and humidity within the kiln between the point, or points of control namely, at the controller bulbs, and at the surface of the stock most remote from the control bulbs in the cycle of either 40 transverse or longitudinal circulation. The amount of this difference necessarily depends upon the rate of circulation within the kiln. It is essential to maintain this differential at a practicable minimum at the different stages of 45 the drying process. At the beginning of the drying process a considerable volume of air circulation within the kiln is necessary to reduce this differential to this practicable amount. At a later stage of the drying process when the evaporation rate from the stock is low, considerably less circulation may be employed and yet maintain this 50 differential within this practicable amount. In other words, variable speed circulation is employed during the drying process to prevent 55 large changes in this differential at the different stages, and also to give the desired accuracy of control in the drying of the stock at the different stages.

60 An economical advantage in the operation of my kilns may be gained by the employment of means for varying the speed of the fans at different stages of the drying operations. In that regard, I have discovered that more driving force is necessary to effect increased rate of circulation of the drying atmosphere of the kiln 65 when the stock loads are first introduced into the kiln in a wet or green state, that when afterwards they have given off a portion of their moisture content. The reason appears to be that the gaseous medium of circulation, in passing through the interstices of the stock loads, takes up so much of the moisture therefrom in passing through part of the load as to incapacitate it for taking up a corresponding portion of moisture in 70 passing through the remainder of the load. In

other words, the drying atmosphere of the kiln functionates to better advantage in passing through part of the distance it has to travel in passing through the interstices of the load than it does in passing through the remainder of the 5 distance. The remedy for that condition is to increase the rate or volume of circulation during such periods as the stock is wet and the condition above indicated continues. This requires increase of power for such period. After the 10 stock becomes drier, the reduction of its moisture content diminishes gradually the necessity for the higher rate of circulation, and permits reduction of the rate of speed of circulation and of the power necessary to effect it. In other words, 15 the rate of speed of circulation is by my invention made proportionate to the lag in the capacity of the circulating medium to absorb moisture in passing across the surfaces of the drying stock loads. The term lag is, in this connection, 20 defined to be loss of the functioning capacity of the drying atmosphere, taking into consideration that such capacity is diminished by loss of heat from the drying atmosphere, as well as by increase of the moisture content thereof. The 25 rate of circulation desired is that which will render the drying operation on the stock loads as uniform as possible, throughout its different stages.

Hitherto, a substantially constant rate of speed 30 has been imparted to the fans throughout the whole period of the drying operation of the kiln. My invention contemplates economy in the saving of power, for instance, through the employment of means for driving the fans at different 35 speeds or of interrupting the operation of the fans altogether and relying in such case upon natural draft for effecting circulation in different stages of the drying operation, proportionate to the condition, at any stage, of the drying 40 atmosphere, as affected, for example, by the stock to be dried. My invention in this regard, consists in using fans of variable speed and in setting their speed proportionately to the amount of work demanded of them at different stages of 45 the drying operation.

It is deemed unnecessary to give a further description of the operation of my invention. However, it may be said that by employing greater volume of air circulation at the beginning of the 50 drying process, and a lesser volume of air circulation at a later stage after the fibre saturation point of the stock has been reached, I am able to effect a corresponding change in the effectiveness of the heating system, humidifying 55 system and ventilating system, which latter includes both fresh air intake and air outlet from the kiln. The greater volume of air circulation during one stage produces a greater heating effect from the heating system, produces a greater humidifying effect by evaporating more water from the stock and produces a greater amount of ventilation by accelerating the action of the fresh air ports and ventilators. Correspondingly, a reduction in the rate of circulation at a later stage 65 reduces the effectiveness of each of the above systems.

It is intended that this application be a continuation in part of application Serial #204,022 filed July 7, 1927, now Patent #1,891,060 issued 70 Dec. 13, 1932.

It is understood that this invention is not limited to the exact design and form illustrated and described. Modifications of the principles herein described and mechanical equivalents are self- 75

evident to those skilled in the art; therefore, it is to be understood that the invention includes within its scope whatever changes fairly come within either the terms or the spirit of the appended claims.

Having described my invention, what I claim is:

1. In a dry kiln having enclosure defining walls, means for the accommodation of stock loads stacked therein, means for circulating kiln atmosphere therein, said means comprising fans operatively mounted therein and distributed throughout the length of the kiln, the fans at one end of said kiln being of less air circulating capacity than the fans at the opposite end of said kiln, heating means within said kiln, said heating means being of greater heating capacity at the end of the kiln having fans of less air circulating capacity, and being of lesser heating capacity at the end of the kiln having fans of greater air circulating capacity.

2. In a dry kiln, a series of fans operatively mounted on a longitudinal shaft and distributed thereon substantially the full length of the kiln, the fans at one end being of larger diameter than the fans at the other end of the kiln, a heating system extending in part the full length of the kiln, said heating system having greater heating capacity at the end having smaller fans, and less heating capacity at the end having larger fans.

3. In a progressive kiln having green and dry ends, and stock supporting tracks therein suitable for accommodating material to be dried, a return bend heating system in part extending the full length of the kiln, individual heating means, ventilating means and humidifying means disposed at one end of the kiln, air circulating means comprising fans operatively distributed substantially the full length of the kiln, said fans having greater air circulating capacity at the green end, and lesser air circulating capacity at the dry end thereof, said return bend heat-

ing system having more heating surface at the dry end of the kiln.

4. In a dry kiln, a separate air circulating system comprising fans at each end, a separate heating system at each end, a separate humidifying system at each end, means for changing the speed of rotation of the fans of said air circulating systems, controllers for said heating and humidifying systems, said controllers comprising means for actuating said speed changing means, whereby the speed of rotation of the fans is increased when the humidity adjacent thereto is equal to or higher than a predetermined amount and the speed of rotation of the fans is reduced when said humidity is lower than a predetermined amount.

5. In a dry kiln, an air circulating system comprising fans therein distributed substantially its full length, a separate heating and humidifying system at each end of the kiln, means for changing the speed of rotation of the fans of said air circulating system, a controller for said heating and humidifying systems for maintaining a predetermined humidity, said controller comprising means for reducing the speed of said fans, when the humidity is lower than the predetermined humidity and increasing the speed of the fans when the humidity is equal to or higher than the predetermined amount.

6. In a dry kiln, a separate air circulating system at each end, a separate humidifying spray at each end, a controller for the wet bulb temperature at each end, said controller comprising means for reducing the rate of air circulation at each end and adding humidity by opening said humidifying spray when the wet bulb temperature is lower than a predetermined amount and for increasing the rate of circulation of said air circulating system and closing said humidifying spray, when the wet bulb temperature is at or above the predetermined amount, whereby stock varying in moisture content at each end of the kiln may be given separate treatment.

JAMES FORREST COBB.
